UNITED STATES PATENT OFFICE.

VARA L. PACE, OF BEAUMONT, TEXAS.

BUILDING-BLOCK.

1,367,497.

Specification of Letters Patent.

Patented Feb. 1, 1921.

Application filed December 17, 1919. Serial No. 345,472.

To all whom it may concern:

Be it known that I, VARA L. PACE, a citizen of the United States, residing at Beaumont, in the county of Jefferson, State of Texas, have invented certain new and useful Improvements in Building-Blocks; and I do hereby declare the following to be a full, clear, and exact description of the invention, such as will enable others skilled in the art 10 to which it appertains to make and use the same.

This invention relates to masonry and concrete structures, and more especially to walls made up of interlocked blocks laid in 15 tiers; and the object of the same is to produce a block or wall unit of this kind capable of being molded or otherwise formed easily, laid rapidly in tiers with the blocks in one tier or row breaking joint with those 20 in the next subjacent tier, and having interlocking tongue-and-groove elements which automatically engage as the blocks are laid and yet which are in such position on each block that they are protected from injury 25 during rough handling. The block is by preference made with flat ends or extremities, although the configuration thereof forms no part of the present invention. The block is also by preference shaped on 30 its front and rear faces to form a cling for the facing on the outside and the plastering on the inside, if these are used, although this feature is also susceptible of modification, and in fact the outer face of the block may 35 be ornamented and left exposed if preferred. As seen in Figure 3 of the drawings below, ventilation may be produced by erecting a double wall of these blocks with an air space between. In fact, the block may be solid 40 or otherwise, reinforced or not, of any appropriate size and material, and provided with other details of construction not set forth herein.

The essential features of the invention are 45 disclosed in the following specification and claim, reference being had to the drawings wherein:

Fig. 1 is a perspective view of one of these blocks.

50 Fig. 2 is an elevation showing a wall being erected by the use of these blocks.

Fig. 3 is a plan view of a double wall being built from the same.

In what might be called the front elevation 55 this block is rectangular in its general contour, being of greater dimension longi-

tudinally than it is vertically. We are not concerned with the third dimension which is its thickness, and I may say here that its outer face 1 which is presented toward the reader in Figs. 1 and 2 is shown as having a marginal rabbet 2 which in effect will produce an undercut groove if this face is left exposed or will serve as a cling to retain a plastic facing F if the same is later applied to the wall. The rear face may be similarly formed or not, or may have a different type of cling serving to retain the plastering P if such is later applied. These details are unimportant and the widest latitude with respect thereto is reserved. The ends or end faces 3 of the block are herein shown as flat and are illustrated in Fig. 2 as abutting each other squarely, but here again the possibility of elaboration is apparent, as these faces 75 might be made irregular to receive the mortar or other cement in which the blocks are laid and by which they are tied, and it is quite possible that such end faces could be provided with vertical tongue and grooves 80 for positively interlocking, since the blocks are laid by a strictly vertical movement as will be explained. While the blocks might possibly be provided with upright openings adapted to align when they are laid in tiers 85 and staggered, I prefer to secure ventilation by building a double wall as illustrated in Fig. 3, and in that event the two thicknesses would doubtless be tied together in some way not necessary to elaborate. Half blocks 90 will also be made for the ends of a wall or the corners, as well understood by those skilled in the art and therefore not necessary to illustrate. Finally, the drawings show the various blocks in close abutting contact, 95 but it is to be understood that their mating faces will be constructed with provision for the interposition of the mortar or cement by which the blocks are connected.

In front elevation each block is substantially H-shaped and includes a horizontal web which is relatively thin, uniting two upright heads which are relatively thick, or to state it differently, the body of the block has transverse channels 4 and 5 extending across 105 its upper and lower faces from its front to its rear face, and leaving transverse ribs at the ends of the channels, the upper ribs being numbered 6 and 7 and the lower ribs 8 and 9, these ribs being the projecting ends 110 of the two heads of the H-shaped structure. While each rib extends entirely across the

block from front to rear, its length at right angles to this direction is one-quarter of that of the block, the channel 4 being one-half the length of the block, or in other words occupying the central two-quarters while the ends occupy the endmost two quarters.

The bottom wall 10 of each channel is by preference flat, and the end walls 11 are oblique, diverging outward from the extremities of the bottom wall as seen. These end walls of the channel form also the inner faces of the ribs, and the quarter lines on which the length of the block is divided would of course intersect the oblique end walls at their centers, while the intermediate or central line would bisect the bottom 10. The end walls of the upper channel are provided with upright grooves 12, their bottoms diverging in parallelism with the faces of the top wall. The end walls of the lower channel are also flat. Its end walls are provided with lugs or tongues 13, each slightly smaller than one of the grooves just described, its inner edge inclining outward and downward. The upper and lower faces of the ribs are also flat, and the end faces 3 of the block are flat as already stated. An advantage arises from having considerable flat surfaces at the top and bottom and ends of any building block, because while irregularities therein may be complemented by contiguous blocks during erection of most of the wall, there are numerous instances where no similar block will be contiguous. For instance, the lower tier of blocks will rest on the foundation or sill, the upper tier will underlie the plate, the ends of many blocks will define the corners of a building or come against the sides of a door frame or window frame. I have purposely avoided the formation of any tongues or grooves in those faces of this block which are likely to abut some flat element, and thereby I secure the greatest area of contact and the least chance that a projection such as a tongue 13 might be broken off.

In Fig. 2 a wall composed of these blocks is being laid, and several blocks in the lower

tier are in place, while one block A in the tier above is already in place and two adjacent blocks B and C are about to be laid. It will be observed that the ribs 8 and 9 of block A pass over the ribs 7 and 6 of the two blocks in the subjacent tier, or in other words, the lower channel 5 of the block A has received the two ribs of the blocks below it. The rib 9 of block B is about to descend into the unoccupied left half of the upper channel in the subjacent block, its extremity 3 sliding against that of the block A, and its tongue 13 ready to pass into the groove 12 which is seen in dotted lines. So also the block C is about to be dropped into place. When the second row has been fully laid upon the first row, the blocks in the former will break joint with those in the latter and will interlock with them. No block can then move endwise nor forward or backward, no block can descend, and only those in the upper row can rise; and these will of course be prevented from rising when the next row or tier is laid upon them. Therefore a wall constructed of building blocks so made and so locked possesses great strength, and yet all the advantages first mentioned above are present. Having built the wall it may be faced as at F and plastered as at P, and otherwise finished in a manner not necessary to elaborate.

What I claim is:

A substantially rectangular building block whose upper and lower faces have transverse ribs at their ends flat at top and bottom and transverse channels between the ribs also flat at top and bottom, each channel being of a size to receive two such ribs, the end walls of one channel having upright grooves and those of the other channel having tongues to fit such grooves in two blocks in the next tier.

In testimony whereof, I affix my signature, in the presence of two witnesses.

VARA L. PACE.
